DOUGH CUTTER

Rinda Shaw, Chicago, Ill.

Application March 31, 1949, Serial No. 1,731

Term of patent 7 years

(Cl. D44—29)

To all whom it may concern:

Be it known that I, Rinda Shaw, a citizen of the United States, residing at Chicago, in the county of Cook and State of Illinois, have invented a new, original, and ornamental Design for a Dough Cutter, of which the following is a specification, reference being made to the accompanying drawing, forming a part thereof.

In the drawing:

dough cutter taken from a point removed by 90° from the point of view represented in Figure 4.

I claim:

The ornamental design for a dough cutter, substantially as shown.

RINDA SHAW.
